(57) **CLAIM**

I claim the ornamental design for a pourer with closure, as shown and described.

DESCRIPTION

The intended use of the pourer with closure is for mounting in the discharge opening of a container.

FIG. 1 is a front perspective view of the pourer with closure showing my new design;

FIG. 2 is a front perspective view of the pourer with closure of FIG. 1 with the closure removed for full disclosure;

FIG. 3 is a bottom perspective view thereof;

FIG. 4 is a cross sectional view thereof;

FIG. 5 is a side view thereof;

FIG. 6 is a top view thereof;

FIG. 7 is a bottom view thereof; and,

FIG. 8 is a bottom perspective view of the pourer with closure with the pourer removed for full disclosure;

FIG. 9 is a top perspective view thereof;

FIG. 10 is a cross sectional view thereof;

FIG. 11 is a side view thereof;

FIG. 12 is a top view thereof; and,

FIG. 13 is a bottom view thereof.
